UNITED STATES PATENT OFFICE

LARS GOTTFRID PERSSON, OF NEW YORK, N. Y., ASSIGNOR TO A. B. SEE ELEVATOR COMPANY, INC., A CORPORATION OF DELAWARE

ELEVATOR CAR GUIDE

Application filed February 14, 1930. Serial No. 428,304.

This invention provides means which will positively prevent the frame of an elevator car from becoming deformed and allowing the guide shoes and safety device on one side to leave the guide rail, the tendency to do which occurs, for example, when a car is much more heavily loaded on one side than it is on the other and the safety devices are caused to operate. When a car is largely or wholly loaded on one side of the center line and an accident occurs which places the car out of control so that it acquires a speed which calls the safety devices into play, the unbalanced condition requires a stronger retarding force on the heavily loaded side than on the lightly loaded side, and since the safety devices are constructed to hold equally on each side, the cross members of the car frame tend to pivot on the side of the car that is lightly loaded with the result that if this tendency is great enough the heavily loaded side of the car swings off the guide rail altogether.

By this invention, I provide means which cooperate with the head of the rail to prevent such a contingency. The invention is conveniently applied with the type of guide rail which is coming more generally into use, namely, one having an enlarged head joined to the base by a web and having a general resemblance to the rails employed on railroads. Upon the vertical side frame members of the car, usually though not necessarily, for their full length, I provide an angle member which extends behind the head of the guide rail. Preferably, there will be two opposed angle members which run behind the head of the rail on opposite sides of the web. These will normally be just out of contact with the rear of the head of the rail but sufficiently close to prevent any material movement of the cross beams of the car frame on their heavily loaded ends after they have come to rest on their lightly loaded ends. In other words, the frame of the car is prevented from deformation by the tendency of the cross frame members to pivot about their lightly loaded ends. As long as the car is running under control the flanges of the angle members are out of contact with the heads of the rails and do not come into play. It is only when the car is

brought to the sudden stop occasioned by the safety devices and there is a sufficient lack of balance in the loading of the car to cause the car frame to warp sufficiently to bring the flanges on the heavily loaded side against the rear of the rail head, that these angle members function and prevent the safety devices on that side from leaving the rail altogether.

It is apparent that such angle irons have sufficient inherent strength for the purpose. Specifically I prefer to apply these angle irons to the side frame members of the car by attaching them to the flanges of an extra channel member which is secured to the outer face of each side frame member. This channel member serves as an extra reinforcement to the side frame members and affords them the requisite strength to sustain his load when the angle members are called into play to prevent the side of the car from leaving the rail. The construction is such that they may be the full length of the height of the car and their length will prevent their becoming overheated from the friction when they engage the rail head.

I shall now describe the illustrated embodiment of my invention and shall thereafter point out my invention in claims:

Fig. 1 is an elevation of the frame of an elevator car in an elevator hatchway;

Fig. 2 is a section on the line 2—2 of Fig. 1;

Fig. 3 is a longitudinal side elevation of the same; and

Fig. 4 is an enlarged section of a guide rail and the cooperating members on the side of the elevator car.

In the construction illustrated in the drawing, there is shown the frame 1 of an elevator car, the details of the car being omitted for the sake of simplicity and the clearer illustration of the features of the invention. The car is shown in an elevator hatchway 2. To opposite sides of the hatchway, there are secured guide rails 3. The guide rails consist of a base or flange 4 which is adapted to be secured to the side of the hatchway, a web 5 extending perpendicularly from the base 4, and an enlarged head portion 6. The guide rails run longitudinally of the hatchway 100

from from top to bottom and are adapted to guide the elevator in the shaft.

On the elevator car, secured to the upper and lower cross beams adjacent the guide rails 1, there are elevator guide shoes 7 of the usual type. The shoes engage the enlarged head portion of the guide rails on three sides thereof to restrain movement of the elevator car with respect to the guide rails in directions lateral to the side engaging faces of the guide shoes. Lateral movement of the elevator, i. e., movement in a direction away from the side of the hatchway to which the guide rail is secured, is restrained during normal operation of the elevator by the guide rail on the opposite side of the hatchway and its cooperating guide shoe. If the car is loaded out of balance and the car runs away so that the safety devices operate, additional means are provided to prevent the heavily loaded side from leaving the rail.

In the construction shown, these additional means are on the outer face of the channel shape members 8 which constitute the side frame members of the elevator car and extend the entire height of the car. To the outer face of each member 8, between the flanges thereof, is secured a second and narrower channel shape member 9. The flanges 10 of the channel shape member 9 extend laterally from the side of the car on either side of the enlarged head portion 6 of the guide rail. To each of the flanges 10 of the channel shape member 9, there is secured an angle member having flanges 11 and 12, the flange 11 being secured to the member 10, and the flange 12 extending around the enlarged head of the guide rail in close proximity to the web of the guide rail.

In the illustrated construction, the channel members 9 and the angle members secured to the flanges thereof extend the entire height of the car. It is to be understood, however, that the length of these members need only be such as to distribute the forces exerted thereon over a sufficient area to maintain the safety devices in engagement with the guide rails, and also, to provide sufficient engaging area so that heat generated by frictional engagement between these members and the guide rails will not cause the fusing of the members to the guide rail.

From the above description of the illustrated embodiment of my invention, it will be apparent that the safety devices will be held positively to the guide rails on each side of the car irrespective of the condition of loading of the car and a possible difference in the momentum of the two sides of the car when the safety devices operate.

It is obvious that various changes may be made in the embodiment illustrated in the drawing and above particularly described within the principle and scope of my invention as expressed in the appended claims.

I claim:

1. In an elevator car, in combination with vertical guide rails disposed on opposite sides of a hatchway and having each an enlarged guide head, the frame of the car, two guide shoes on either side of the car attached to the frame thereof, one shoe being on top of the frame and the other on bottom of the frame and each having a channel shape bearing surface engaging over the adjacent side rail, and vertical angle members on the side frame members of the car between the guide shoes extending behind the enlarged head of the adjacent guide rail and the guide shoes acting to maintain the angle members out of contact with the head but in close proximity thereto.

2. In an elevator car, in combination with vertical guide rails disposed on opposite sides of a hatchway and having each an enlarged guide head, the frame of the car, and opposed vertical angle members on opposite side frame members of the car extending substantially the full length of the frame members, the opposed flanges of the members on each side running behind the enlarged head of the adjacent rail out of contact with the head but in close proximity thereto.

3. In an elevator car, in combination with vertical guide rails disposed on opposite sides of a hatchway and having each an enlarged guide head, the frame of the car, a vertical channel member secured to the side frame member on each side of the car in opposition to the respective guide rail, and two angle members secured to the flanges of each channel member, the two angle members on each side having their outer flanges extending inwardly immediately behind the enlarged rail and spaced to receive the web of the guide rail between them.

4. In an elevator car, in combination with vertical guide rails disposed on opposite sides of a hatchway and having each an enlarged guide head, the frame of the car, a vertical channel member secured to the side frame member on each side of the car of substantially the length of the side frame member and disposed in opposition to the respective guide rail, and two angle members secured to the flanges of each channel member and substantially corresponding thereto in length, the two angle members on each side having their outer flanges extending inwardly immediately behind and out of contact with the enlarged rail and spaced to receive the web of the guide rail between them.

In witness whereof I hereunto subscribe my signature.

LARS GOTTFRID PERSSON.
